UNITED STATES PATENT OFFICE.

FRANK P. HOLLOWAY, OF KNOXVILLE, TENNESSEE, ASSIGNOR TO FAIR FOUNDRY CO.,
OF KNOXVILLE, TENNESSEE, A CORPORATION OF TENNESSEE.

STOVE.

Application filed September 2, 1922. Serial No. 585,930.

To all whom it may concern:

Be it known that I, FRANK P. HOLLOWAY, a citizen of the United States, and resident of Knoxville, Tennessee, have invented new and useful Improvements in Stoves, which invention is fully set forth in the following specification.

This invention relates to improvements in stoves. While designed especially with reference to coal and coke burning heating stoves, the improvements constituting the invention are applicable to stoves, heaters, or furnaces, generally.

Amongst the principal objects attained are the provision of a structure which lends itself to ease and simplicity of repairs in that all of the main parts within the casing or drum may be taken out and replaced through a door of the stove without the use of any tools whatsoever; provision of a combined fire-bowl and grate support, preferably of substantially annular outline and formed of a plurality, preferably two, of interchangeable sections interlocking with each other when assembled in place and formed from the same pattern; the provision of a fire-bowl in the form of a plurality of interchangeable sections, all of one pattern, and adapted when assembled to rest at their lower edges on the aforesaid support; the provision of simple means for supporting the combined fire-bowl and grate support whereby said support may be readily put in place or removed, as desired; the provision of parts such as the aforesaid, and particularly the fire-bowl sections, so formed and supported when assembled as to admit of expansion in service without binding or wedging such as to interfere with ready removal of parts in making repairs, thereby avoiding the necessity of breaking such parts in order to effect removal thereof as is commonly the case with structures now ordinarily used; and the provision of a structure which by interchangeability of parts such as aforesaid minimizes the number of different parts required to be carried by dealers and also correspondingly reduces the liability of mistakes in filling repair orders and assembling the parts in making repairs. The aforesaid and still other objects herein-after stated or apparent from the description and drawings are realized by what I at

present regard as the preferred embodiment of my invention illustrated in the accompanying drawings wherein—

Fig. 1 is a perspective view of a heating stove of well known type in conjunction with which my invention is illustrated as more particularly shown in other views of the drawings;

Fig. 2 is a vertical sectional view through a portion of one side of the stove of Fig. 1;

Fig. 3 is a top view of the combined fire-bowl and grate support;

Fig. 4 is a horizontal sectional view showing the overlapping of edges of two sections of the fire-bowl;

Fig. 5 is a perspective view of assembled parts of the stove omitting the top, the enclosing drum or casing, and three of the five fire-bowl sections;

Fig. 6 is a bottom view of one of the two sections which constitute the combined fire-bowl and grate support; and

Fig. 7 is an outside view of one of the sections of the fire-bowl.

The base 10 of the stove is shown as supported by four legs and as having a bottom 11 constituting the floor of the ash chamber. Around its edge base 10 is formed with an upstanding annular flange 13 and on the inside of said flange with a horizontal offset or shoulder 14 between which and the floor 11 there is an upright wall 15. 16 are supporting posts of which there are three all of like construction spaced 90° apart around the base 10. At its lower end each post is offset to form a notch or recess 17 closely fitting over the shoulder formed by the walls 14 and 15 with the extreme lower end surface of the post bearing against the upper surface of the bottom or floor 11 of the base. Opposite each post 16 there is an upstanding lug 18 on the base rising above the flange 13 with its inner face flush with the inner face of said flange. The lower edge of the sheet metal drum or casing 19 fits closely inside of the flange 13 and lugs 18 on the base and rests against the horizontal wall 14 or shoulder 14. The three posts 16 stand upright inside of the drum 19 close to the interior surface thereof as best shown in Fig. 2. A screw 20 passing first through a washer, then through a hole in the lug 18, through an opening in the drum 19, through

another washer interposed between the inner surface of the drum and the outer surface of the post 16, thence through an opening in the post 16, and engaged at its inner end by 5 a nut, serves to hold the parts together at the lower end of each post. At its upper end each post 16 is formed to provide an upstanding lug 21 with horizontal supporting surfaces 22, 22 at opposite sides thereof. 10 25 is the ash door frame positioned over a suitable opening through the drum or casing 19, secured to said drum around its upper edges by suitable screw bolts as shown in Fig. 1, and at its lower edge fitting the base 15 10 and secured thereto by a screw bolt 26, Fig. 5. The upper or fuel door of the stove is hinged to a suitable door frame 27 positioned over an opening through the wall of the drum or casing 19 and secured thereto 20 by screw-bolts as best shown in Fig. 1.

A combined fire-bowl and grate support is shown as constituted by two similarly formed interchangeable approximately semi-circular sections 30, 30, each having 25 at one end thereof a projecting tongue 31 with a lug 32 thereon, and at its other end a tongue receiving socket 33 with a cross bar 34 across the open end thereof. When the two sections 30, 30 are assembled and interlocked to constitute the complete annular support, the tongue 31 at one end of each section is engaged in the socket 33 at the other end of each section, with the bottom surface of each tongue bearing downward 30 against the bottom wall of the socket and the top surface of each tongue engaging upward against the underside of the cross bar 34, and with the lug 32 on each tongue engaging behind the cross bar 34 of its 35 socket, as clearly shown in Fig. 3. In this position of the parts the engagement of the tongues and sockets will afford the same strength in resisting downward pressure as if the two sections were made in one piece, 40 while a lifting of the two sections at their points of interlocking will disengage the lugs 32 from behind the cross bars 34 and permit the two sections to be readily drawn apart and disconnected for removal separately 45 from the interior of the drum. Around the inner semi-circular edge of each support section 30 there is an upstanding flange 35, and around the outer edge thereof a succession of spaced equidistant upstanding lugs 36 and 37, with the end surfaces of 50 the cross bars 34, 34 constituting in effect similar lugs. The lugs 37 are larger and longer than the lugs 36, each extending outward over and serving to reinforce a peripherally projecting lug 38 of which there 55 are two on each section 30 and so positioned that when the two sections 30, 30 are interlocked there will be four lugs 38 spaced 90° apart. Each lug 38 is notched 60 to fit over the lug 21 at the upper end of

the post 16 and to rest on the horizontal surfaces or ledges 22 at opposite sides of lug 21. One of the four notched lugs 38 will engage over a lug 39 cast on the inner surface of the ash door frame 25, and at opposite sides of said lug will rest upon horizontal surfaces also formed on said ash door frame, the shape of lug 39 and its adjacent supporting surfaces being similar to that at the upper end of the posts. The 70 upper ends of the three posts 16 and the lug 39 on the ash door frame being equally spaced at 90° from each other and similarly formed, any one thereof may be engaged by any one of the four similarly 75 formed notched lugs 38 of the combined fire-bowl and grate support, the manner of engagement resisting downward pressure or weight but readily permitting disconnection and removal of the two sections by upward 80 or lifting movement. On each support section 30 there are also two depending inwardly projecting grate supporting lugs or arms 40, 40 so positioned that when the two sections 30, 30 are assembled, as shown in 85 Fig. 3, these lugs 40 will be positioned 90° apart. The grate 41, which as illustrated is of a type ordinarily used in hot blast stoves, rests upon and is removably supported by the four lugs 40, as shown in Fig. 5. 90

The upwardly flaring cylindrical fire-bowl is shown as made up of five similarly formed interchangeable sections 42, each section being vertically slotted to provide for ventilation and also having along one upright edge thereof what may be termed an expansion flange 43 adapted to form an overlapping joint with the adjacent edge of the adjoining section and being also of sufficient width to take up any possible expansion of the fire-bowl sections during their life. A lug 44 is cast on the outer surface of each fire-bowl section 42 near the top and near the edge thereof which is overlapped by the flange of the adjacent 100 section. As shown in full lines, Fig. 4, said lug is thus so positioned as to properly space the sections when new and at the same time so formed that when expansion 105 takes place as the result of service, the flange 43 of the adjoining section will ride over said lug, as shown in dotted lines Fig. 4, without causing disarrangement of the fire-bowl sections. The outwardly curved upper edges of the fire-bowl sections 42 110 rest against the inner surface of the metal drum or casing 19. At its lower end each section 42 is formed around its inner edge with a notch 45 which engages over the flange 35 of the combined fire-bowl and 115 grate support, said lower edge of the fire-bowl sections also fitting freely between the outer upright surface of the flange 35 and the inner upright edges of the upstanding lugs 36 and 37 and across bars 34, where- 120 125 130

by each fire-bowl section is confined in place at its lower edge by engaging what is in effect a channel or groove, with the flange 35 also serving as an inside guard protecting the entire support, of which it is a part, from any intense heat. As will be apparent, special positioning of the fire-bowl sections along the support therefor is unnecessary as no matter where the lower edge of a section 10 is positioned along the flange 35, a plurality of lugs 36, 37 will be opposed to the outer surface thereof to hold the lower end of the section in place. The fire-bowl sections 42 are of such size and shape that 15 they may be readily introduced through the fuel door and properly positioned in engagement with the combined fire-bowl and grate support and with relation to each other by manipulation thereof by reaching 20 through said door. In the event of necessary repairs or replacements said sections may be readily loosened and removed through the fuel door, the grate 41 removed through the same door, the two sections 30, 25 30 of the combined support relatively lifted so as to disengage their interlocking tongues and sockets and permit removal of said sections separately through the same door, and all of this, as well as reassemblage of said 30 parts, can be accomplished with facility without the use of tools or fastening means such as bolts, screws, etc. A lug 46 on the inner face of each fire-bowl section near the top thereof may be gripped in handling and 35 positioning said section.

What I claim as new is:—

1. In a stove, the combination of a combined grate and fire-bowl support constituted of a plurality of separable sections assembled end to end and having interengaging means at their adjoining ends, a grate detachably and removably mounted on and supported by said support, and a fire-bowl detachably and removably mounted on and 45 supported by said support.

2. In a stove, the combination of a combined grate and fire-bowl support constituted of a plurality of separable sections assembled end to end and having interengaging means at their adjoining ends, a grate mounted on and supported by said support, and a fire-bowl constituted of a plurality of sections mounted on and supported by said support.

55 3. In a stove, the combination of a combined grate and fire-bowl support constituted of a plurality of separable interchangeable sections assembled end to end and having interengaging means at their adjoining ends, a grate mounted on and supported by said support, and a fire-bowl constituted of a plurality of interchangeable sections mounted on and supported by said support.

4. In a stove, the combination of a support constituted of a plurality of separable

interchangeable sections assembled end to end and having interengaging means at their adjoining ends, and a fire-bowl constituted of a plurality of separable interchangeable sections mounted on and supported by said support. 70

5. In a stove, the combination of a substantially cylindrical fire-pot comprising a plurality of interchangeable sections, a grate, and an approximately circular frame 75 comprising a plurality of approximately arcuate interchangeable interlocking sections and supporting both said fire-pot and grate.

6. In a stove, the combination of a plurality of standards secured to the base thereof, a frame comprising a plurality of interchangeable sections having interlocking engagement with the upper ends of said standards, a grate removably mounted on 80 said frame, and a sectional fire-pot removably mounted on said frame and bearing against the side wall of the stove.

7. In a stove, the combination of a base, a plurality of vertical standards secured to said base, a sectional frame removably mounted on said standards, said frame having an upstanding flange and inwardly projecting lugs, a grate resting on said lugs, a sectional fire-pot engaging said flange and supported by said frame, and a casing 90 mounted on said base and having a fuel door opening through which removal and replacement of said grate and sectional parts of the 95 frame and fire-pot may be made.

8. In a stove, the combination of a casing having a door opening therein, a supporting frame mounted in said casing and comprising a plurality of interchangeable sections adapted to interlock end to end to constitute 105 a frame having an open center and said sections being detachable from each other for removal through said door opening of the casing, and a grate mounted on and supported by said support.

9. In a stove, the combination of a casing having a door opening therein, a supporting frame mounted in said casing and comprising a plurality of interchangeable sections adapted to interlock end to end to constitute 115 a frame having an open center and said sections being detachable from each other for removal through said door opening of the casing, and a fire bowl mounted on and supported by said support.

10. In a stove, the combination of a casing having a door opening therein, a combined fire-bowl and grate supporting frame removably mounted in said casing and comprising a plurality of interlocking sections 125 assembled end to end to constitute a continuous frame with an open center, a grate and a sectional fire-pot both mounted on and supported by said support, said grate and said sectional elements of both said support 130

1
and fire-bowl being removable and replaceable through said opening to provide for repairs or renewal of the parts.

11. In a stove, the combination of a plurality of frame supporting elements having lugs thereon, a sectional frame having outwardly extending lugs adapted to interlock with the lugs on said frame supporting elements, and the sections of said frame having interlocking means at the ends thereof for detachably connecting the same together, inwardly extending lugs on said frame for supporting a grate, a flange on the upper side of said frame adapted to be engaged by the lower edge of a fire-pot, and lugs for holding said fire-pot in engagement with said flange.

12. A stove comprising a base, a casing mounted on said base, frame supporting elements secured to said base within said casing, a sectional frame removably mounted on said frame supporting elements, and said frame having a flange and spaced lugs on its upper side and also inwardly projecting lugs, a grate supported on said inwardly projecting lugs, and a fire-pot mounted on said frame and comprising a plurality of sections having overlapping side edges and the lower edges of said sections engaging between the flange and lugs on the upper side of said frame.

In testimony whereof I have signed this specification.

FRANK P. HOLLOWAY.
